UNITED STATES PATENT OFFICE.

JOHN PEARSALL, OF NEW YORK, N. Y.

CARPET-FASTENER.

SPECIFICATION forming part of Letters Patent No. 314,053, dated March 17, 1885.

Application filed January 7, 1885. (No model.)

To all whom it may concern:

Be it known that I, JOHN PEARSALL, of the city, county, and State of New York, have invented a new and Improved Carpet-Fastener, 5 of which the following is a full, clear, and exact description.

Reference is to be had to the accompanying drawings, forming part of this specification, in which similar letters of reference indicate corresponding parts in all the figures.

Figure 1 is a perspective view of a part of a floor and carpet showing the manner of using 15 my new carpet-fastener. Fig. 2 is a plan view of the fastening-plate removed from the carpet. Fig. 3 is a sectional elevation of the floor, carpet, and fastening-plate, the latter being hooked over the nail driven in the floor; and Fig. 4 is a similar view showing a modification of the fastening-plate.

20 My invention is an improvement in the class of carpet-fasteners which consist of a small and thin metal plate provided with an aperture to receive the head of a nail, and adapted for attachment to the under side of a carpet.

25 The improvement consists in the plate having the construction hereinafter described.

Referring to the drawings, A represents the carpet, B the floor, C the fastening-plate, and

30 D the headed nail driven into the floor.

The fastening-plate C is by preference struck from sheet-brass in triangular shape, with the

orifices a at the angles by which the plate may be stretched to the carpet. In its center the plate C has the opening E made in it, which 35 is made large at b for the passage of the head of the nail D, and small at c for engaging the plate with the nail, and the plate C is depressed about the central opening, E, as shown at d, Fig. 3, to form a recess for the head of 40 the nail, so that it will not bulge the carpet, and so that it will freely enter the slot E in the plate.

Instead of forming the plate with a depression, d, the plate may be made concaved, as 45 shown in Fig. 4.

By this construction a carpet cannot be torn or otherwise injured by contact with the head of the nail, and the attachment to or detachment from the latter may be easily and quickly effected.

What I claim is—

The improved carpet-fastener consisting of the metal plate C, provided with the key-hole slot d, and depressed along its middle 55 portion adjacent to said slot to receive the head of the carpet-nail, the remaining portion or edge of the plate being elevated at a uniform height around its entire circumference, as shown and described.

JOHN PEARSALL.
